UNITED STATES PATENT OFFICE.

WILLIAM JACKSON SCHOONOVER, OF BELVIDERE, ILLINOIS.

GEARING FOR WASHING-MACHINES.

1,247,726.

Specification of Letters Patent. Patented Nov. 27, 1917.

Application filed March 26, 1917. Serial No. 157,406.

To all whom it may concern:

Be it known that I, WILLIAM JACKSON SCHOONOVER, a citizen of the United States, and a resident of Belvidere, in the county of 5 Boone and State of Illinois, have invented certain new and useful Improvements in Gearing for Washing-Machines, of which the following is a full, clear, and exact specification.

10 My invention is concerned with gearing for washing machines, and is designed to produce a gearing of the class described that shall be suitable primarily for hand-operated lever washing-machines of the vacuum 15 or pounder type, in which the operating mechanism extends upward through the bottom of the tub.

It is concerned more especially with a 20 gearing of the class described in which the fly-wheel rotates in a horizontal plane, and also with a novel form of mechanism for rotating the spider carrying the cups on the non-rotating shaft that reciprocates up and down through the bottom of the tub.

25 To illustrate my invention, I have annexed hereto four sheets of drawings, in which the same reference characters are used to designate identical parts in all the figures, of which,

30 Figure 1 is a central vertical section through a washing-machine employing my novel gearing;

Fig. 2 is a top plan view as seen in section on the line 2—2 of Fig. 1;

35 Fig. 3 is a view, on an enlarged scale, as seen in section on the line 3—3 of Fig. 1;

Fig. 4 is a vertical section as seen on the line 4—4 of Fig. 3;

Fig. 5 is an enlarged detail of the mechanism appearing in section in Fig. 1;

Fig. 6 is a plan view as seen in section on the line 6—6 of Fig. 5;

Fig. 7 is a detail as seen in side elevation from the left-hand side of Fig. 5;

45 Fig. 8 is a plan view as seen in section on the line 8—8 of Fig. 5;

Fig. 9, Sheet 3, is an enlarged detail illustrating the locking connections between the vertically reciprocating shaft and the spider 50 rotatably mounted on the upper end thereof; and

Fig. 10 is a plan view as seen in section on the line 10—10 of Fig. 9.

I have shown my invention as applied to 55 the ordinary tub 10 having the four legs 11, the bottom 12, and the lid 13 which is hinged

on the top of the tub in any suitable manner so that it can be lifted to remove the contents or observe the operation of the machine. To gain additional space for the 60 gearing, I preferably employ the cap 14 covering an aperture 15 in the lid located centrally of the tub.

Pivoted in a fulcrumed bracket 16 suitably secured on the side of the tub is the 65 operating hand-lever 17, which may be of any desired construction, and which may be provided with the stirrup 18 at its lower end, so that foot-power can also be applied. Pivoted near the lower end of 70 the hand lever 17 is the pitman 19, the other end of which is pivoted on the eccentric bearing pin 20 mounted in the bevel gear-wheel 21 mounted to rotate on the horizontal stub shaft 22 pinned in the bearing 75 bracket 23, which in turn is secured, as by the set screw 24, on the upper end of the vertical bearing shaft 25, the lower end of which is seated in and supported by the bearing 26 formed in the main horizontal 80 portion 27 of a bearing bracket which is secured on the two cross pieces 28 which are secured to and connect the lower portions of the legs 11. The last-mentioned bearing bracket has the pair of horizontal portions 85 29, each of which has the short upright portions 30 having the shape of an angle iron, and running into the inclined portions 31 having the same cross section, which inclined portions in turn run into the elongated vertical portions 32, which in turn are preferably connected at their upper ends by the horizontal plate 33 which rests against the under side of the bottom of the tub and is conveniently secured thereto by 90 the nut 34 screwed on the threaded lower end of the vertical bearing-sleeve 35, which is mounted in the center of the bottom of the tub, it having the horizontal flange 36 resting on said bottom, as clearly seen in Fig. 1. 95

To steady the movement of the gearing and avoid the possibility of its stopping on dead centers, I journal on the upright bearing-shaft 25, between the bracket 23 and the bearing 26, the hub of a heavy fly-wheel 37, 100 which has the bevel pinion 38 secured thereon meshing with the bevel gear-wheel 21, so that as the handle 17 is swung back and forth slowly, the fly-wheel 37 will be rotated at a comparatively high speed.

105 Mounted to reciprocate in the vertical bearing-sleeve 35 is the vertical shaft 39,

which has the spider 40 secured on its upper end by the mechanism which will be hereinafter described. Secured on the lower end of this shaft 39 is a guide plate having 5 the collar 41 at its back, which is pinned to the lower end of the rod 39, the guide plate proper 42 having a pair of parallel, horizontal flanges between which reciprocates the elongated sliding block 43 pinned on the 10 adjacent end of the shaft 20, which is free to turn in its bearing in the bevel gear-wheel 21. By the connections thus described, it will be obvious that the shaft 39 will be reciprocated each time the handle 17 is reciprocated, and it will further be observed 15 that the guide plate 42 is in turn guided in its vertical movement by its contact with the vertical portions 32 of the main bearing bracket located beneath the tub.

20 The spider 40 has the central hub 44 and the downwardly and outwardly extended arms 45, which have the plurality, preferably three, of cups 46 secured on the ends thereof to engage the clothes being washed in the customary manner. The spider is 25 free to rotate on the upper end of the shaft, which is provided with the annular groove 47, into which is swung the latchpiece 48, best seen in Fig. 10, which is pivoted at 49 30 and can swing back and forth in the horizontal recess 50 formed in the hub 44 to accommodate it. A latch 51 is pivoted to the hub at 52 and swings down over the latch 48 and holds the same in its operative position. With the construction just described, 35 it will be obvious that the spider 40 is free to rotate on the upper end of the shaft 39, but that it can be readily removed, when desired, by raising the lid, raising the latch 51, and finally swinging out the latch 48. By this simple connection, I can easily 40 remove the spider and the cups 46, as is desirable in putting in a fresh lot of clothes or in wringing out those that have been already washed.

To give the spider 40, and consequently the cups 46, a slight angular movement about the shaft 39 at each reciprocation so that the cups will strike the clothes in a 50 new place each time, I employ the following mechanism:

Secured near the upper end of the shaft 39, as best seen in Fig. 5, by the set-screw 53, is the collar 54, in which is mounted 55 eccentrically the rod 55, the upper end of which is circular and is free to rotate in the circular aperture in the collar 54 through which it passes. A flanged collar 56 secured on the upper end of the rod 55 rests on the 60 collar 54, and pivoted loosely on the upper end of this collar 56, as by the pin 57, is a dog 58, the shape of which is best seen in Fig. 7, the overweighted nose of which tends to engage the teeth 59 formed on the under 65 side of the hub 44, preferably by being

stamped into the periphery of the circular plate 60 secured on the under side of the hub. The portion of the rod 55 below the collar 54 is square in cross section, and cooperates with a snugly fitting squared aperture 61 formed at one side in the top of the sleeve 35. This sleeve 35 carries the rib 62 extending along one side thereof, and the aperture 61 is located in the rib 62. The squared aperture 61 leads into a larger circular aperture 63 extending the length of the rib 62 to accommodate the twisted portion of the rod 55, which is twisted so as to cause it to be given a slight rotation as it rises and falls through the squared aperture 61 during the reciprocation of the rod 39. This rotation causes the dog 58 to swing over a sufficient number of ratchet teeth 59 to advance the spider the desired number of degrees at each reciprocation.

70 While I have shown and described my invention as embodied in the form which I at present consider best adapted to carry out its purposes, it will be understood that it is capable of modifications, and that I do not desire to be limited in the interpretation of the following claims except as may be necessitated by the state of the prior art.

80 What I claim as new, and desire to secure by Letters Patent of the United States, is:

85 1. In a gearing, the combination with a support, of a vertical bearing-sleeve extending therethrough, a shaft mounted to reciprocate lengthwise in the sleeve, a bevel gear-wheel journaled adjacent one end of the 100 shaft, means connecting the gear wheel and the shaft to reciprocate the latter as the wheel rotates, means to rotate the wheel, a fly-wheel journaled in a plane at right angles to the plane of the gear wheel, and 105 a bevel pinion on the hub of the fly-wheel meshing with the gear-wheel.

110 2. In a gearing, the combination with a support, of a vertical bearing-sleeve extending therethrough, a shaft mounted to reciprocate lengthwise in the sleeve, a bevel gear-wheel journaled adjacent one end of the shaft, means connecting the gear wheel and the shaft to reciprocate the latter as the wheel rotates, a fly-wheel journaled in a 115 plane at right angles to the plane of the gear wheel, a bevel pinion on the hub of the fly-wheel meshing with the gear-wheel, a lever fulcrumed on the support, an eccentric pin on the bevel gear-wheel, connections between the eccentric pin and the shaft to reciprocate the latter as the gear wheel rotates, and a pitman connecting the load end of the lever and the eccentric pin.

120 3. In a gearing, the combination with a support, of a vertical bearing-sleeve extending therethrough, a shaft mounted to reciprocate lengthwise in the sleeve, a bevel gear-wheel journaled adjacent one end of the shaft, a cross head on the bottom of the 125

shaft, an eccentric pin carried by the bevel gear-wheel extending into the slot of the cross head, a fly-wheel journaled in a plane at right angles to the plane of the gear wheel, a bevel pinion on the hub of the fly-wheel meshing with the gear wheel, and a pitman connecting the lever and eccentric pin.

4. In a gearing, the combination with a 10 horizontal support, of a vertical bearing-sleeve extending therethrough, a shaft mounted to reciprocate lengthwise in the sleeve, legs for the horizontal support, cross braces for the legs, a bracket connecting the 15 cross braces and the under side of the support, a vertical stud projecting upward from the bracket, a fly-wheel journaled on the stud, a bevel pinion secured to the hub of the fly-wheel, a secondary bracket secured 20 on the top of the vertical bearing-stud, a horizontal bearing-stud projecting from the secondary bracket, a bevel gear-wheel journaled on the horizontal bearing-stud and meshing with the bevel pinion, means for 25 rotating the bevel gear-wheel, and connections between the bevel gear-wheel and the shaft to reciprocate the latter lengthwise as the bevel gear-wheel rotates.

5. In a gearing, the combination with a 30 horizontal support, of a vertical bearing-sleeve extending therethrough, a shaft mounted to reciprocate lengthwise in the sleeve, legs for the horizontal support, cross braces for the legs, a bracket connecting the 35 cross braces and the under side of the support, a vertical stud projecting upward from the bracket, a fly-wheel journaled on the stud, a bevel pinion secured to the hub of the fly-wheel, a secondary bracket secured 40 on the top of the vertical bearing-stud, a horizontal bearing-stud projecting from the secondary bracket, a bevel gear-wheel journaled on the horizontal bearing-stud and meshing with the bevel pinion, means for 45 rotating the bevel gear-wheel, and connections between the bevel gear-wheel and the shaft to reciprocate the latter lengthwise as the bevel gear-wheel rotates, said connections comprising a cross head on the bottom 50 of the vertical reciprocating shaft, an eccentrically mounted bearing-pin carried by the bevel gear-wheel and extending into the slot of the cross head, and a pair of vertical arms carried by the bracket forming guides 55 for the cross head.

6. In a gearing, the combination with a horizontal support, of a vertical bearing-sleeve extending therethrough, a shaft mounted to reciprocate lengthwise in the 60 sleeve, legs for the support, cross braces for the legs, a bracket connecting the cross braces and the under side of the support, the upper end of the bracket being secured to the lower end of the vertical bearing-sleeve, 65 said bracket comprising a pair of vertical

arms forming a bearing for the cross head, said arms diverging at their lower portion and being united by a cross piece resting on the cross braces, a vertical bearing-stud supported in the cross piece, a fly-wheel journaled on the vertical bearing-stud, a bevel pinion secured on the upper side of the hub of the fly-wheel, a secondary bearing-bracket secured on the upper end of the vertical bearing-stud, a horizontal bearing-stud secured in the upper end of the secondary bracket, a bevel gear-wheel mounted on the horizontal bearing-stud and meshing with the bevel pinion, a slotted cross-head secured to the lower end of the reciprocating shaft, 70 a block sliding in the slotted cross-head, a pin secured to the block and likewise journaled eccentrically in the bevel gear-wheel, an operating lever fulcrumed on the support, and a pitman connecting the load end 75 of the lever and the bearing pin.

7. In a gearing, the combination with a support, of a vertical bearing-sleeve extending therethrough, a shaft mounted to reciprocate lengthwise in the sleeve, means 80 connected with the lower end thereof for reciprocating the same, a spider supported on the upper end of the shaft, and latching mechanism for removably securing the spider on the shaft.

8. In a gearing, the combination with a support, of a vertical bearing-sleeve extending therethrough, a shaft mounted to reciprocate lengthwise in the sleeve, means 85 connected with the lower end thereof for reciprocating the same, a spider mounted to rotate on the upper end of the shaft, means interposed between the shaft and the spider to rotate the latter step by step as the shaft reciprocates, and latching mechanism for removably securing the spider on the shaft.

9. In a gearing, the combination with a support, of a vertical bearing-sleeve extending therethrough, means connected with the 90 lower end thereof for reciprocating the same, a spider mounted to rotate on the upper end of the shaft, a ratchet carried by the hub of the spider, a pivoted dog supported from the shaft and adapted to 95 engage the ratchet, means connected to the shaft for swinging the dog as the shaft is reciprocated, and latching mechanism for removably securing the spider on the shaft.

10. In a gearing, the combination with a 100 support, of a vertical bearing-sleeve extending therethrough, means connected with the lower end thereof for reciprocating the same, a spider mounted to rotate on the upper end of the shaft, a ratchet carried 105 by the hub of the spider, a pivoted dog supported from the shaft and adapted to engage the ratchet, an angular aperture carried by the hub of the sleeve, a rod parallel to the shaft journaled at its upper end in 110

4
a bearing carried by the shaft and having its body portion extending through and of the same angular cross-section as the angular aperture, said body portion being twisted for the purpose described, said dog being pivoted on the upper end of the rod, and latching mechanism for removably securing the spider on the shaft.

11. In a gearing, the combination with a support, of a vertical bearing-sleeve extending therethrough, a shaft mounted to reciprocate lengthwise in the sleeve, means connected with the lower end thereof for reciprocating the same, a spider mounted to rotate on the upper end of the shaft, an annular groove in the upper end of the shaft, a latch pivoted on the hub of the spider and adapted to enter the annular groove, and a second latch coöperating with the first to hold it in the groove.

12. In a gearing, the combination with a support, of a vertical bearing-sleeve extend-

ing therethrough, a shaft mounted to reciprocate lengthwise in the sleeve, means connected with the lower end thereof for reciprocating the same, a spider mounted on the upper end of the shaft, a ratchet carried by the hub of the spider, an angular aperture carried by the top of the sleeve, a rod parallel to the shaft journaled at its upper end in a bearing carried by said shaft and having its body portion extending through and of the same angular cross-section as the angular aperture, said body portion being twisted for the purpose described, and a pawl pivoted on the upper end of the rod and engaging the ratchet.

In witness whereof, I have hereunto set my hand and affixed my seal, this 21st day of March, A. D. 1917.

WILLIAM JACKSON SCHOOONOVER. [L. S.]

Witness:

JOHN HOWARD McELROY.
